VIBRATORY SCREEN

Munroe F. Warner, Columbus, Ohio, assignor to
 American Zinc, Lead & Smelting Company,
 St. Louis, Mo., a corporation of Maine

Application May 12, 1938, Serial No. 207,633

7 Claims. (Cl. 209—346)

This invention relates to vibrating screens and to the particular means for mounting the same whereby the vibration of the screen can be more efficiently effected and which, when certain classes of material are being screened, can be operated with minimum injury to the structure as a whole.

Existing screens of the vibrating type are of two general designs, in one of which the screen cloth is stretched and attached rigidly within a frame and the entire frame vibrated. In this case the mass or weight to be vibrated is greater than is desirable and imposes heavy loads upon the vibrator and bearings, and results in severe reaction on the foundations and supports. In the other type the screen cloth is stretched between simple springs for light service, the vibrator being attached directly to the screen cloth so that the screen cloth itself is directly vibrated thereby. In this case vibration is intense in the middle of the screen area, where the vibrating mechanism is attached, and is to a great degree diminished or even absent at the edges and ends of the screen surface.

One of the objects of the present invention is to so mount the screen cloth that the entire screen surface shall be free to vibrate and at the same time reduce the mass or weight to be vibrated. This is accomplished by providing a device or devices which shall be free to move within required limits in a direction normal to the screen surface during vibration, which devices are carried by fixed or non-vibrating supports.

The inventive idea is capable of receiving a variety of mechanical embodiments, some of which for the purpose of illustrating the invention are shown in the accompanying drawings, but it is to be expressly understood that such drawings are for the purpose of illustration only and are not designed to define the limits of the invention, reference being had to the appended claims for this purpose.

In said drawings—

Fig. 1 is a plan view partially broken away, illustrating two forms of one embodiment of the invention;

Fig. 2 is an end elevation of Fig. 1;

Fig. 3 is an enlarged sectional detail of the construction shown in Fig. 1;

Fig. 4 is a plan view partially broken away showing a modification of the invention;

Fig. 5 is an end elevation of the construction shown in Fig. 4;

Fig. 6 is an enlarged section in detail of the construction shown in Fig. 4;

Fig. 7 is a plan view with parts broken away of still another modification;

Fig. 8 is an elevation of Fig. 7;

Fig. 9 is an enlarged sectional view of the structure shown in Fig. 7;

Fig. 9a is a detail section showing a slight modification of Fig. 9; and

Fig. 10 illustrates a still further modification of Fig. 9.

Referring to the drawings in which like reference numerals indicate like parts throughout the several views, 1—1 indicate stationary side bars mounted on any suitable supporting structure, not shown, one of these bars being placed on each side of the screen structure, and 2—2 indicate screen anchors preferably right angular in cross section, as shown in Fig. 3. These screen anchors are placed between the respective side bars, one adjacent to each side bar. These screen anchors are each yieldingly connected to the respective side bars of the structure to the end that the screen anchors may have a vibrating move-

ment up and down with relation to the side bars and in a plane approximately normal to the screen cloth. As shown in Fig. 3, the screen anchors 2 have a bearing block or a plurality of bearing blocks 2' rigidly connected thereto and extending upward therefrom so that the blocks 2' constitute in effect an upward extension of the screen anchors. These blocks 2' have formed therein, on the side adjacent to the side bars 1, a groove 2'', and a second bearing block or strip 1' is rigidly secured to the inner face of the side bar. This bearing block 1' has formed therein a groove 1'' approximately opposite and preferably slightly below the groove 2'' in the bearing block 2', and a bar 3, preferably having rounded edges, extends between and takes pivotal bearing in the two grooves 1'' and 2'', the bar 3 preferably, although not necessarily extending slightly in an upward and inward direction from the side bar 1. The construction just described constitutes a yielding connection be-

tween the screen anchor 2 and side bar 1 and by reason of the inward and upward inclination of the member 3 affords an efficient support for the screen and its load. There may be a series of bars 3 placed at several points along the side bar, as shown in the left of Fig. 1, or the same

may be a continuous bar 3, as shown in the right of Fig. 1 and extending the full length of the screen, but in either construction the yield-

ing action is in a plane approximately normal to the screen cloth.

On the exterior of each side bar 1 is mounted a bearing seat 4 (Fig. 3) for a spring 5, the outer 5 end of the spring taking against a follower 6 through which follower extends a pin 7 hinged to the bearing block 2' at 8 so as to permit the pin 7 to move in a vertical plane around the pin 1. The exterior end of the pin 7 is screw threaded and has a nut 9 thereon, whereby the follower is forced inward against the spring to place the same under compression.

A series of these spring devices is placed along each side of the structure, and in operation the 15 nuts 9 are tightened until the rods 7 are brought to a horizontal position and centered within the springs, at which point the screen cloth will be properly tightened and its tension counterbalanced by the springs.

20 The screen cloth 10 is stretched between the screen anchors 2, preferably with the edges of the screen cloth turned around and over the horizontal arm of the screen anchors, as shown at 10' in Fig. 3, but it is to be understood that 25 any efficient means for securing the screen cloth to the screen anchors may be employed.

Now, referring to Figs. 4, 5 and 6, there 30 is therein shown a modification in which the same spring construction 5 illustrated in connection with Fig. 1 is also employed, together with the same screen anchors and upwardly extending elements 2'. In this structure the yielding connection of the screen anchor to the side bars takes the form of a hinge. A series of 35 upwardly and inwardly inclined bars 11 (Fig. 6) are pivoted to the upper end of anchor extension 2' by a pin 12 and to the side bar 1 by a pin 13 to the end that the screen anchors and with them the screen cloth may be free to move 40 up and down with relation to the side bars. The pins 12 and 13 may extend the entire length of the screen as at the right in Fig. 4, or there may be a separate pair of pins 12 and 13 for each hinge bar as at the left of Fig. 4. As in the 45 case of the bar construction heretofore described, there may be a plurality of bars 11, one located at each of the spring tension devices (see left of Fig. 4), or if desired, there may be a continuous series of hinge members along the full length of 50 the screen and hinged to the side bars 1 and the anchors 2 as at the right of Fig. 4.

Referring now to Figs. 7, 8, 9, 9a and 10, there 55 is shown therein the same spring device 5 as that described in connection with Figs. 1 to 6, inclusive. In the construction shown in Fig. 9, the screen anchors 2 are yieldingly connected to the side bars 1 by means of spring bars 15 extending from points outside of the side bars and through openings therein and to a point above the 60 anchor bar 2 where each bar 15 is rigidly secured thereto. The exterior end of the spring bar 15 is mounted in a housing 17 rigidly secured to the exterior of the side bars, the spring bar being rigidly bolted within the housing as shown. 65 By this construction a yielding connection is afforded between the anchor bar and the side bar. Such yielding connection is obtained in a modified form by the construction shown in Fig. 9a in which the spring arm 15 is hinged to the 70 screen anchor 2.

Instead of providing an elastic bar 15, as shown in Fig. 9 and depending upon the resiliency of the bar itself to respond to the vibrations, a rigid bar 15' (Fig. 10) may be employed hinged at its 75 inner end to the screen anchor 2, with its outer

end in the housing 17', which housing is rigidly secured to the exterior of the side bar 1. Resilient material, such as rubber, is mounted in the housing on each side of the rigid bar 15', to the end that the end of the bar 15', where it is 5 hinged to the screen anchor 2, may be permitted to move similar to that of the spring bar 15, shown in Fig. 9.

It will be observed that whatever be the form of yielding connection employed between the side 10 bars and the screen anchors, the pivotal connection of the spring tension device is connected to the anchor bars at a point intermediate said yielding connection and the point where the screen cloth is attached to the screen anchor. 15

Whatever form of yielding connection employed between the side bars and screen anchors may be, any suitable vibration mechanism, such as electromagnetic vibrators 19, may be employed, and such vibrators may be connected to 20 the screen at any desired point as at the center 20 (Figs. 2 and 5) or at the edges or corners of the screen as at 21 (Figs. 2 and 8).

It will be noted that the screen cloth is free to vibrate without vibrating the stationary side 25 bars.

Whatever form of yielding connection between the side bars and screen anchors is employed, cover plates 22, 22 are secured to the interior side 30 of each side bar 1 and extend down below the top of the screen anchors or extensions thereof.

It will be appreciated that by means of the construction herein described, there is provided means which yieldingly connect each of the screen anchors to its adjacent side bar, such 35 yielding means taking the form of pivoted bars (Figs. 1 to 3), or other yielding hinge constructions (Figs. 4 to 6, inclusive), or the yielding bar construction (Figs. 7 to 10, inclusive), the essential feature being that when the screen is 40 stretched by means of the tension springs 5 and set in vibration by any suitable vibrating mechanism, the screen support, to wit, the screen anchors, are able to move freely and rapidly in an up and down direction so that the entire body 45 of the screen cloth is subjected to practically uniform vibration. Furthermore, it will be observed that the mountings for the screen are not of such mass or weight as to deaden or materially influence the vibrations. 50

What is claimed is:

1. In a screen device, the combination of a pair of oppositely disposed stationary side bars, screen anchors between said side bars, one adjacent each of said bars, said screen anchors each having an extension member rigidly secured thereto, yielding connections between said extension members and said side bars and inclined upwardly and inwardly from the side bars, a screen cloth connected to the screen anchors, spring tension 60 means pivoted to said extension members between said yielding connections and the screen cloth connections to the screen anchors, and means vibrating the screen.

2. In a screen device, the combination of a pair 65 of oppositely disposed side bars, screen anchors between said side bars, one adjacent each of said bars, said screen anchors each having an upwardly extending member rigidly secured thereto, hinge connections between said extension members and said side bars and having members inclined upwardly and inwardly from the side bars, a screen cloth connected to the screen anchors, spring tension means pivoted to said extension members between said hinge connections 70 75

and the screen cloth connections, and means vibrating the screen.

3. In a screen device, the combination of a pair of oppositely disposed side bars, screen anchors between said side bars, one adjacent each of said bars, said screen anchors each having an extension member rigidly secured thereto, rocking bar connections between said extension members and said side bars and inclined upwardly and inwardly from the side bars, spring tension means pivoted to said extension members below said rocking bar connections, a screen cloth secured to and extending between the screen anchors, and means vibrating the screen.

4. In a screen device, the combination of a pair of oppositely disposed stationary side bars, screen anchors between said side bars, one adjacent each of said bars, said screen anchors each having an extension member rigidly secured thereto, yielding connections between said extension members and said side bars, a screen cloth connected to the screen anchors, spring tension means pivoted to said extension members between said yielding connections and the screen cloth connections to the screen anchors, and means vibrating the screen, relative to the side bars and in a plane substantially normal to its surface.

5. In a screen device, the combination of a pair of oppositely disposed stationary side bars, screen anchors between said side bars, one adjacent each of said bars, said screen anchors each having an upwardly extending member rigidly secured thereto, hinge connections between said extension members and said side bars, a screen cloth connected to the screen anchors, spring ten-

sion means pivoted to said extension members between said hinge connections and the screen cloth connections, and means vibrating the screen, relative to the side bars and in a plane substantially normal to its surface.

6. In a screen device, the combination of a pair of oppositely disposed stationary side bars, screen anchors between said side bars, one adjacent each of said bars, said screen anchors each having an extension member rigidly secured thereto, rocking bar connections between said extension members and said side bars, spring tension means pivoted to said extension members below said rocking bar connections, a screen cloth secured to and extending between the screen anchors, and means vibrating the screen, relative to the side bars and in a plane substantially normal to its surface.

7. In a screen device the combination of oppositely disposed stationary side bars, a screen cloth, screen cloth anchors adjacent each of said side bars, yielding connecting bars extending longitudinally of the side bars along a line substantially parallel to said screen cloth anchors and forming yielding connections between said side bars and screen cloth anchors, yielding tension means pivotally connected to said screen cloth anchors between said screen cloth and said connecting bars and reacting against said side bars and putting the screen cloth under tension, and means vibrating the screen cloth, relative to the side bars and in a plane substantially normal to its surface.

MUNROE F. WARNER. 35
